FIG. 13 is a second perspective view of the fenestration screen assembly of FIG. 12 in an open configuration.
 FIG. 14 is a first sectional view of the fenestration screen assembly of FIG. 12 taken along line 14-14 in FIG. 12.
 FIG. 15 is a second sectional view of the fenestration screen assembly of FIG. 12 taken along line 15-15 in FIG. 12.
 FIG. 16 is a front view of the fenestration screen assembly of FIG. 12.
 FIG. 17 is a back view of the fenestration screen assembly of FIG. 12.
 FIG. 18 is a top view of the fenestration screen assembly of FIG. 12.
 FIG. 19 is a bottom view of the fenestration screen assembly of FIG. 12.
 FIG. 20 is a first side view of the fenestration screen assembly of FIG. 12.
 FIG. 21 is a second side view of the fenestration screen assembly of FIG. 12; and,
 FIG. 22 is a third perspective view of the fenestration screen assembly of FIG. 12.
 The broken lines are directed to environment, are for illustration purposes only, and form no part of the claimed design.
